UNITED STATES PATENT OFFICE

WARREN S. BELLows, OF EAST ORANGE, NEW JERSEY

DETACHABLE CONNECTION FOR WRENCH SOCKETS AND THE LIKE

Application filed August 26, 1925. Serial No. 52,500.

This invention relates to an improvement in socket wrenches and other detachable connections.

It is an object of the invention to provide a socket wrench having detachable sockets of various sizes, and to provide means whereby the sockets may be securely locked to the shank of the wrench when in use, or whereby other detachable shaft sections may be locked together.

Another object of the invention is to provide a socket wrench of the type described, in which the connection between the wrench socket and the shank will be reinforced so as to prevent separation of the connecting members due to service strains or other causes.

Another object of the invention is to provide a detachable connection between wrench sockets and the shanks therefor, in which the engaging portions of the connection will be enclosed in and protected by a substantially smooth surrounding collar which is an integral part of the connection.

Various other objects and advantages of the invention will appear as a description thereof proceeds.

Referring to the drawings which illustrate the preferred form of embodiment of the invention.

Fig. 1 is a side elevation, partially in section, showing the connection between the shank and socket.

Fig. 2 is a detail view of the lower end of the shank, showing the parts in a different position from that of Fig. 1.

Fig. 3 is a side elevation of the socket member, detached from the shank.

Fig. 4 is a sectional view of the connection between the shank and socket member, taken on the line 4-4 of Fig. 1.

Fig. 5 is a sectional view on the line 5-5 of Fig. 1, showing the collar in socket locking position.

Fig. 6 is a bottom sectional view of the lower end of the wrench shank.

Fig. 7 is a side view of the wrench socket, taken approximately at right angles to the view of Fig. 3.

In the embodiment of the invention chosen

for the purpose of illustration, the wrench comprises a shank portion 1, which may be provided at the upper end thereof with a means for receiving a turning member 2 which may comprise a detachable rod passing through a hole 3 in the upper end of the shank member, and held against removal therefrom by spring-pressed ball 4.

The lower end of the shank is preferably enlarged as at 5, and is provided with a slot 6 through the center thereof, separating the lower end of the shank into two segment-shaped projections or prong members 7. The outer circumference of the prongs 7 is provided with an annular groove 8 and the lower end 5 of the shank is surrounded by a collar 9 which extends substantially to the end of the projections 7 and which provides a means for holding these projections against any tendency to spread when the shank is used for turning the wrench socket.

The collar 9 is provided with an interior groove 10 which receives a pair of spring-pressed balls 11, mounted in the portion 5 of the shank, and is provided with a pair of diametrically opposite holes 10^a, adapted to receive the balls 11 to removably hold the collar in position to lock the wrench socket to the shank. The collar 9 is also provided on the interior thereof with a pair of lugs 12 which are of the same width and depth as the groove 8 and project into this groove.

The wrench socket 13 is provided with a nut engaging hole or opening 14, which may be of various sizes in different sockets, and is provided with a flat top portion 15 from which a tongue or slab 16 projects upward at approximately the center thereof and extends substantially from side to side of the socket 13.

The tongue 16 is adapted to fit snugly into the slot 6 in the lower end of the wrench shank 1 and is provided with grooves 17 which register with the groove 8 in the prongs 7 when the shank and wrench socket are brought together in operative position.

The parts of the wrench are assembled by first providing the shank 1 with a slot 6, groove 8 and the spring-pressed balls 11 and 100

forming the collar 9 with the lugs 12 projecting from the inner walls thereof, the lugs 12 being of slightly less length than the width of the slot 6. The balls 11 are then pushed into the wall of the shank 1 and the collar 9 slipped upon the same with the lugs 12 sliding through the slot 6 until the balls 11 are projected into the slot 10 of the collar, in which position the lugs 12 are in registry with the slot 8 in the prongs 7 and the collar 10 can be rotated on the shank to turn the lugs 12 into the slot 8 in the prongs 7. When the lugs 12 are moved out of the slot 6 the tongue 16 of the wrench socket may be pushed into 15 the slot 6 until the ends of the prongs 7 contact with the top 15 of the wrench socket, in which position the slots 17 will register with the slot 8 and the collar 9 may then be turned to move the lugs 12 into position where they 20 extend partly into the slot 8 in the prongs 7 and partly into the slots 17 in the tongue 16 to thereby lock the socket against removal from the shank.

The holes 10^a in the collar are preferably 25 located so that the balls 11 will be projected thereinto when the lugs 12 occupy a position approximately as indicated in Fig. 5. In this way the lug 12 locks the socket in the shank and also locks the collar upon the 30 shank so that neither the collar, shank nor socket is permitted longitudinal movement relative to the other.

It will be noted that the steps of connecting the shank to the socket member are 35 extremely simple and the connection is quite effective. No longitudinal movement of the collar on the shank is necessary for this connection, it being only necessary to insert the tongue 16 of the socket into the slot 6 of the shank and rotate the collar until the balls 11 spring into the holes 10^a to releasably hold the collar from further rotation. It is obvious that if the balls 11 prevent rotation, the socket is positively secured to the 40 shank and sleeve by the lugs 12 and the lugs 12 are prevented from loosening. The balls therefore act as a supplementary locking means, supplementing the lugs 12.

The tongue and slot connection between 45 the socket member and the shank is of unusual strength and the prongs 7 have slight tendency to spread when the wrench is used for turning a recalcitrant bolt or nut.

The integral collar 9 surrounding the 50 prongs 7 and the tongue 16 effectively prevents any tendency to spread and the detachable connection formed by this manner is much stronger than the usual form of detachable connection of a wrench socket and shank, and also easy to operate for connecting or disconnecting a socket.

The wrench also presents a neat appearance and a smooth exterior, so that very 55 slight danger of injury to the hands or

clothing exists in the use of this type of connection on power driven machines.

I have described a preferred form of embodiment of my invention. It is to be understood, however, that various modifications and changes may be made therein without departing from the spirit of the invention or the scope of the appended claims, and that the connection shown is not confined solely to use with socket wrenches. 75

I claim:

1. In a device of the character described, the combination of a shank having a smooth surfaced cylindrical end provided with an open longitudinal slot and a transverse groove 80 communicating with said slot, a wrench socket, a tongue projecting from said socket adapted to fit snugly in said slot and provided with notches adapted to register with said groove, a sleeve adapted to fit over said cylindrical end provided with interior lugs adapted to pass thru said slot when the sleeve is assembled on said shank, and to fit snugly in said groove and said notches, thereby securing the shank, wrench socket and sleeve in assem- 90 bled relation.

2. In a detachable wrench socket connection, in combination, a shank having an integral cylindrical end, provided with an open longitudinal slot and an exterior transverse 95 groove communicating with said slot, a wrench socket having an upwardly extending tongue adapted to fit snugly in said slot and provided with notches adapted to register with said groove, a sleeve adapted to fit over the cylindrical end of said shank provided with lugs adapted in assembly to pass through said slot and to be turned into said groove to permit the insertion in said slot of the wrench socket tongue, said sleeve being rotatable to an effective position in which said lugs simultaneously engage the grooves in the shank and the slots in the tongue thereby holding shank, sleeve and socket in assembled relation, and means for yieldably retaining 100 said sleeve in such effective position.

3. In a detachable wrench socket connection, the combination of a shank and a wrench socket, there being a detachable tongue and slot connection between said shank and wrench socket, a collar rotatably mounted on said shank and surrounding said tongue and slot when connected, there being registering grooves in said tongue and shank, and lugs on 115 said collar adapted to fit in said grooves and to be rotated to simultaneously engage said tongue and shank, securing said shank, tongue and collar in assembled relation.

In testimony whereof I have affixed my signature to this specification. 125

WARREN S. BELLOWES.
